TAPING AND FOLDING MACHINE

James E. McIntire, Peabody, Mass., assignor to
United Shoe Machinery Corporation, Paterson,
N. J., a corporation of New Jersey

Application December 20, 1933, Serial No. 703,323

12 Claims.

(Cl. 12—55)

This invention relates to the application of a reinforcing element to a piece of sheet material and to the application of such a reinforcing element and the subsequent folding of the margin of the piece of sheet material.

In the manufacture of boots and shoes, it is customary to apply to certain parts of the uppers thereof a reinforcing element which is commonly a piece of cord or tape and will be referred to herein, for convenience, as a piece of tape. This tape in some instances is a prepared tape already coated with an adhesive substance; and in other instances, it is coated progressively just prior to its progressive application to the shoe part and before the folding of the margin of said part, by being drawn through a bath of cement, the work-engaging elements of the folding machine, which is commonly used, serving not only to feed the shoe part but also to feed the tape. The tape is supplied in the form of a long strip wound upon a reel; and, whether it is a prepared, coated tape which is drawn directly from the supply reel to the work or is an uncoated tape which is drawn through a cement receptacle before reaching the work, a considerable force is required to pull it along, with the result that a considerable drag is exerted by it upon the forwardly moving work.

In order to obviate this undesirable condition, there is provided, in one aspect of the invention, between the supply reel and the folding machine or between the cement receptacle and the folding machine, a pull-off mechanism which pulls the tape from the reel, and through the cement receptacle, if there is one, and feeds the tape to the folding machine, the pull-off mechanism being operated by the folding machine through an adjustable connection so that the rate of feed of the tape by the pull-off mechanism may be varied with respect to the rate of feed of the work if desired. The illustrated machine comprises a supply reel having a coil of tape, a cement receptacle, a pull-off mechanism for pulling the tape from the reel, drawing it through the cement and feeding it forward, and a mechanism which applies the tape to the work, feeds the work and the tape, and folds the margin of the work, the work-feeding mechanism being adjustably connected with the pull-off mechanism. With such a construction, the tape arrives at the work under no tension, since a small amount of slack is maintained between the pull-off mechanism and the work.

Hitherto when an indeterminate length of tape has been drawn through cement in a receptacle and then applied to a piece of work, the cement used has been a so-called "rubber cement", that is a solution of rubber in naphtha or some similar solvent. When such a cement is used, it does not form immediately a properly sticky coating; and consequently it has been necessary to

lead the coated tape up to the ceiling and back again one or more times, or otherwise to festoon it, in order to permit the solvent to evaporate sufficiently before the coated tape reaches the work so that the coating shall be properly sticky. 5 Aside from the necessity of providing apparatus for such festooning of the coated tape, this method has the more serious disadvantage that at the end of each day's work a considerable length of tape—namely all that which is in festoons when the day's work ceases—must be thrown away since the coating of cement will not be properly sticky on the following morning.

In order to obviate these disadvantages, means are provided for treating the tape with rubber 15 latex and immediately scraping surplus latex from coated surfaces. In the illustrated machine, the tape is drawn through a bath of latex and is then subjected to the action of four scrapers which remove the surplus latex from the entire 20 width of both faces of the tape and from the angularly disposed edges thereof. After such treatment, the tape is properly sticky, does not require to be festooned and may be fed directly to the work, preferably by a pull-off mechanism, 25 as shown. The apparatus hitherto necessary for festooning the tape is thus no longer required, and at the end of the day's work, only a comparatively short length of tape is wasted.

Referring to the accompanying drawings, 30

Fig. 1 is an elevation of a machine for coating tape, applying it to a piece of work and folding the margin of the work by the use of which the method referred to above may be practiced,

Fig. 2 is an elevation of the pull-off mechanism 35 which draws the tape from the supply reel and feeds it toward the work-feeding mechanism of the folding machine,

Fig. 3 is a plan of the mechanism shown in Fig. 2, 40

Fig. 4 is a perspective showing part of the under side of the cover of the cement receptacle and the mounting of the scrapers which remove surplus cement from the tape,

Fig. 5 is a detail in perspective showing the 45 connection of the pull-off mechanism with the work-feeding mechanism of the folding machine,

Fig. 6 is a horizontal section through the stem of the presser foot of the machine showing a 50 piece of work in process of being operated upon, and

Fig. 7 is a view looking down upon the top of the cement receptacle.

Referring first to Fig. 1, the machine comprises three units, a unit indicated as a whole at A 55 which comprises a reel for a supply of tape and a receptacle for cement, a unit indicated as a whole at B which comprises mechanism for pulling the tape from the reel through the cement receptacle and feeding it forward, and a unit C 60

which comprises a folding machine where the tape is applied to the work and the margin of the work is folded over upon it. The folding machine C, except for certain structures to be described later, is or may be the same as the machine disclosed in United States Letters Patent No. 1,702,598, granted February 19, 1929, upon an application filed in the name of Perley R. Glass. In this machine, the work is fed over a table 6 by a cooperating hammer or fold-presser 11 and an anvil 13. The hammer has a four-motion feed movement, and the anvil moves back and forth in the line of feed. The work, such for example as a piece of leather 100 the edge of which has been skived, first encounters a gage or guide 15 (Fig. 6) which bends up the edge of the leather to some extent. It is then acted upon by a reciprocating folding finger 17 which bends the margin of the work about the edge 19 of a creaser or presser 21 to form a fold; and is finally gripped between the hammer and the anvil to cause the fold to be pressed and the work to be fed.

The folding machine herein shown differs from the machine of the patent in several particulars. The creaser or presser 21 is of the shape shown in Figs. 1 and 6 and has an upwardly curved portion extending to the right. In the outer end of this upwardly curved portion there is formed a tape guide 121. To the left of this guide the presser 21 carries a small roll 23; and the under face of the presser has formed in it a groove. The tape passes down through the tape guide 121, beneath the small roll 23 and through the groove in the under face of the presser, the tape being thus directed upon the work 100 in position to be received in the apex of the fold formed by the cooperation of the folding finger 17 with the edge 19 of the presser or creaser 21. The fold is completed and pressed by the descent of the hammer, and the work with the tape enclosed in the fold is then fed to the left by the simultaneous movement of the hammer and the anvil. Mounted on the frame of the machine are a guide roll 25 and a stationary guide 27 for directing the tape from the pull-off mechanism B.

The feed mechanism of the folding machine is utilized to operate the pull-off mechanism B. In the folding machine there is a rod 59 (Fig. 5) mounted for oscillation about an axis which contains the pointed ends of two alined screws, one of which is shown at 61, said rod having integral with it an arm 67. Pivoted to the outer end of this arm is the lower end of the stem 71 of a yoke which is moved up and down to varying extents in accordance with the length of the intermittent feed movements of the hammer and anvil, and hence in accordance with the rate of feed of the work. These movements of the stem 71 cause the rod 59 to oscillate with different amplitudes according to the rate of feed of the work. The mechanism which has just been described, including the parts 59, 67 and 61, is the same as the corresponding mechanism shown in Fig. 8 of the patent wherein the corresponding parts bear the same reference numerals. In the machine of the present application, a second arm 29 is fast at its inner end to the oscillating rod 59 and at its outer end is pivoted to the lower end of a link 31, the upper end of which (Fig. 1) is pivoted at 33 to a small block 35 of the pull-off mechanism so that, as will presently appear, the pull-off mechanism is operated from the oscillating rod 59 in such manner that, as the work-engaging

members of the folding machine feed the work, the pull-off mechanism feeds the tape.

The tape 200 is led from a coil on a reel 37 down through a hole in the cover of a cement receptacle 39, around two small guide rods 41, 43, 5 which are located beneath the surface of the cement, and then up through a second opening in the cover of the cement receptacle and over a guide roll 45 to the pull-off mechanism B. Referring to Figs. 1, 2, and 3, the pull-off mechanism is mounted on a standard 47. Rotatable in bearings in the standard is a shaft 49 which is rotated intermittently in a clockwise direction, as viewed in Fig. 1, by an intermittent grip device actuated by the link 31. Referring to Fig. 2, the 10 intermittent grip device illustrated is in the form of the well-known Horton clutch and includes the usual cage carrying spring-pressed rollers 51. This cage is rigid with a member 53 having driven into it a pin 55 on which the small block 35 is ad- 20 justably mounted. The intermittent grip device will not be described further since the details of its construction form no part of the present invention and any suitable intermittent grip device may be employed. It will be understood, 25 however, that when the link 31 is pulled down (Fig. 2) the roll cage is rocked counterclockwise by the axis of the shaft 49, and the shaft is rotated a short distance counterclockwise, and that when the link is pushed up, the shaft remains 30 stationary. In order to insure that there shall be no backward rotation of the shaft 49, a screw 57 (Fig. 3) bears frictionally with its inner end upon the shaft. The connection between the intermittent grip device and the work-engaging 35 and feeding parts of the folding machine is such that the feeding of the tape by the rotation of the shaft 49 and the feeding of the work by the hammer and anvil take place simultaneously. The shaft 49 is rotated intermittently, as has been 40 explained, by the rocking of the member 53 due to the movement of the link 31 which is pivoted to the small block 35, through a bore in which the pin 55 extends. In order to vary the throw of the pin 55 and the member 53 relative to the extent of the up-and-down movement of the link 31 so as to vary the rate of feed by the pull-off mechanism with respect to the rate of feed of the work, the block 35 is adjustable along the pin 55. To this end, the block has a pin 73 which is 50 slidable through a bore in the member 53 and is integral at one end with the block 35. The other end of the pin 73 (Figs. 2 and 3) has threaded on it a thumb-nut 75 which extends into a slot in the member 53 and is thus held from longitudinal 55 movement. Turning the thumb-nut 75 adjusts the block 35 along the pin 55, and a lock-nut 77 holds the pin and block in adjusted position. Ordinarily, the pull-off mechanism and the work-feeding mechanism feed the tape at the same 60 rate. Some operators, however, pull back on the work as it is going through the folding machine in which case it is desirable that the pull-off mechanism feed the tape a little slower than the folding machine theoretically feeds the work. In 65 any case, however, the pull-off mechanism and the work-feeding mechanism are so adjusted that there is always a little slack in the tape between the pull-off mechanism and the creaser or presser 21 so that the tape is under no tension when it 70 reaches the work.

The shaft 49 at the end opposite to that which carries the intermittent grip device is provided with a toothed grooved lower feed roll 79. Directly above this roll is a similar upper feed roll 75

81, the shaft of which is rotatably mounted in one end of a carrier 85 pivoted near its middle on a shaft 87. A compression spring 89 the tension of which may be varied by turning a screw 91 urges the carrier to swing as far as a stop screw 93 will permit, said screw being threaded through the carrier 85 and contacting with the top of the standard 47. The shaft 49, at the end nearest to the intermittent grip device has a gear 95 which meshes with a gear 97 on a shaft 99 which is rotatable in the standard 47, the latter gear meshing with a gear 101 on the shaft 87, and said gear 101 meshing also with a gear 103 which is fast to the shaft 83 of the upper feed roll 81. In this way the upper and lower feed rolls 81, 79 for the tape are driven intermittently in the direction indicated by the arrows in Figs. 1 and 2. The upper feed roll 81 (Fig. 3) is provided with a scraper or stripper 105 having teeth which extend into the grooves in the roll, the stem of the scraper being fastened by screws 107 on the carrier 85; and the lower feed roll 79 (Fig. 1) is provided with a similar scraper or stripper 109 carried by the standard 47. These members act to keep the rolls clean and to prevent the tape from being accidentally carried around either roll.

The cement preferably employed is an aqueous dispersion of rubber hereinafter referred to as "rubber latex", since it has been found that by using latex and removing the surplus latex from the tape, the tape becomes properly sticky substantially as soon as it leaves the receptacle and may be led directly to the pull-off mechanism. To remove surplus latex from the tape, four scrapers are employed which are best shown in Fig. 4, said scrapers being mounted on the under side of the cover 139 of the cement receptacle. A scraper 111, adapted to contact with the whole width of one face of the tape 200, is slidably mounted in a guideway on the under side of the cover 139, said scraper having extending upwardly from its top (Fig. 7) a threaded stud 113 to receive a wing-nut 115. The stud projects up through a slot 117 in the cover so that, when the wing-nut 115 has been loosened, the scraper may be removed to be cleaned. Normally, the inner side of the stud 113 contacts with the left-hand end of the slot 117 so that, when this scraper is operative, it always occupies the same position. Referring again to Fig. 4, a second scraper 119 for treating the whole of the other face of the tape is slidably mounted in another portion of the same guideway in which the scraper 111 is mounted, said second scraper having a threaded hole 123 to receive the stem of a screw 125 (Fig. 7) which passes through a slot in the cover 139. This second scraper is thus adjustable toward and from the first scraper 111 to provide for tape of different thicknesses. The two scrapers, which have just been described, serve to remove surplus latex from both faces of the tape. In order to remove surplus latex from the edges of the tape positioned at an angle to the faces thereof, two small scrapers 127, 129 (Fig. 4) are provided. These small scrapers have upturned ends which are received in a guideway extending across the scraper 111 and are held in position by screws 131, 133 which pass through transverse slots in the scrapers 127, 129 and are threaded into the scraper 111. The cover 139 of the latex receptacle is made readily removable by providing it with a plurality of slotted ears 135 (Fig. 7) into and out of the slots in which may be swung rods 137 which are pivoted at their lower ends on pivot pins 141 (Fig. 1) carried by the base 143 upon which the

three units A, B and C are mounted. The cement receptacle 39 is also furnished with slotted ears 147 which register with the slotted ears 135 on the cover so that the pivoted rods 137 and their wing-nuts 145 serve not only to hold the cover 139 on the receptacle 39 but to position the receptacle and hold it on the base. Because rubber latex coagulates very readily, the cement receptacle and the scrapers must be frequently cleaned, the common practice being to clean them each day at the end of the day's work. The construction of the cement receptacle and scrapers which has just been described facilitates this cleaning operation. When the wing-nuts 145 have been loosened and the rods 137 swung down, the receptacle 39 may be removed from the base and the cover 139 may be removed from the receptacle. The wing-nut 115 may then be loosened to free the scraper 111 with the two small scrapers which are carried by it. The fourth scraper 119 may be removed after the screw 125 has been taken out. Thus the cement receptacle may readily be detached from the base and the scrapers may readily be detached from the receptacle.

The cement is maintained in the receptacle 39 at the level shown by a barometric feed device comprising an inverted bottle 149 having a spring-pressed valve 151 which opens when the bottle is inverted and placed in the position shown. A bent rod 153 having a horizontal arm covered by a rubber tube 155 and a vertical arm rotatable in a bearing sleeve 157, may be swung into the operative position shown to hold the bottle in place or may be swung out of that position to permit the bottle to be removed. The sleeve is vertically adjustable in a lug 159 and is held in adjusted position by a set screw 161, said lug being integral with the standard 163 which carries at its upper end the axle 165 of the reel 37.

Assuming that the receptacle and scrapers are clean, the end of the tape 200 on the reel is led through a hole in the cover 139, down around the pins 41, 43 and up through the passageway enclosed by the scrapers which are then adjusted into the proper position. The cover is then fastened down, the bottle 149 put in place, and the tape is led through the pull-off mechanism B, through the guides 27, 25 and 121 and then down under the small roll 23 of the presser foot 21. The operator presents to the folding machine a piece of work, for example a piece of leather 100 having a skived margin or a piece of leather or other sheet material having attached to its edge a so-called French binding, the margin of the work preferably having been coated with cement, and operates the folding machine in the usual manner, starting and stopping it and varying the rate of feed of the work as may be necessary. After a number of pieces of work have been operated upon, the tape which connects them may be cut with a pair of scissors.

Although the illustrated machine includes means for coating tape with cement, it should be understood that in case a precoated tape is employed, the coating means may be omitted and the tape led directly from the supply reel to the pull-off mechanism. Further although the machine is particularly adapted to the use of latex as a cement, it should be understood that the machine may be used with the old form of cement, if desired, by festooning the tape in the old, well-known manner, or otherwise drying the cement until it becomes properly sticky.

Having described my invention, what I claim as

- new and desire to secure by Letters Patent of the United States is:
1. A machine for folding the margin of a piece of work and applying a tape to the work having, in combination, means for feeding the work, fold-forming and fold-pressing means, a reel for a supply of tape, mechanism for pulling the tape from the reel and for feeding the tape toward the fold-forming and pressing means, means for directing the tape upon the work, means for operating the pull-off mechanism from the work-feeding means, and means for varying the rate of feed of the pull-off mechanism with respect to the rate of feed of the work-feeding means.
  - 15 2. A machine for folding the margin of a piece of work and applying a tape to the work having, in combination, means for feeding the work, fold-forming and fold-pressing means, a reel for a supply of tape, mechanism for pulling the tape from the reel and for feeding the tape toward the fold-forming and pressing means, means for directing the tape upon the work in position to extend into the fold, means for operating the pull-off mechanism from the work-feeding means, and means for varying the rate of feed of the pull-off mechanism with respect to the rate of feed of the work-feeding means.
  - 20 3. A machine for folding the margin of a piece of work and applying a tape to the work having, in combination, means for feeding the work, fold-forming and fold-pressing means, a reel for a supply of tape, mechanism for pulling the tape from the reel and for feeding the tape toward the fold-forming and pressing means, means for directing the tape upon the work, means including an oscillating lever for intermittently operating the pull-off mechanism, means for oscillating the lever from the work-feeding means, and means for varying the extent of the oscillation of the lever to vary the rate of feed of the tape by the pull-off mechanism.
  - 25 4. A machine for folding the margin of a piece of work and applying a tape to the work having, in combination, means for feeding the work, fold-forming and fold-pressing means, a reel for a supply of tape, a receptacle for cement, a pull-off mechanism for drawing the tape through the cement and for feeding the tape toward the fold-forming and pressing means, means for directing the coated tape upon the work, means for operating the pull-off mechanism from the work-feeding means, and means for varying the rate of feed of the pull-off mechanism with respect to the rate of feed of the work-feeding means.
  - 30 5. A machine for folding the margin of a piece of work and applying a tape to the work having, in combination, means for feeding the work, fold-forming and fold-pressing means, a reel for a supply of tape, a receptacle for cement, a pull-off mechanism for drawing the tape through the cement and or feeding the tape toward the fold-forming and pressing means, means for directing the coated tape upon the work in position to extend into the fold, means for operating the pull-off mechanism from the work-feeding means, and means for varying the rate of feed of the pull-off mechanism with respect to the rate of feed of the work-feeding means.
  - 35 6. A machine for folding the margin of a piece of work and applying a tape to the work having, in combination, means for feeding the work, fold-forming and fold-pressing means, a reel for a supply of tape, a receptacle for cement, a pull-off mechanism for drawing the tape through the cement and presenting it without tension to the directing means.
  - 40 7. A machine for folding the margin of a piece of work and for applying a tape to the work having, in combination, means for feeding the work, fold-forming and fold-pressing means, a receptacle for cement, means for leading the tape through the cement and directing it upon the work in position to be engaged by the work-feeding means, and means for scraping cement from the entire surfaces of both faces of the tape and from an edge of the tape positioned at an angle to said faces before it reaches the work.
  - 45 8. A machine for folding the margin of a piece of work and for applying a tape to the work having, in combination, means for feeding the work, fold-forming and fold-pressing means, a receptacle for cement, means for leading the tape through the cement and directing it upon the work in position to be engaged by the work-feeding means, and a plurality of scrapers mounted on the receptacle in positions to engage the whole widths of both faces of the tape and the angularly related edges thereof.
  - 50 9. A machine for folding the margin of a piece of work and for applying a tape to the work having, in combination, means for feeding the work, fold-forming and fold-pressing means, a receptacle for cement, means for leading the tape through the cement and directing it upon the work in position to be engaged by the work-feeding means, and a plurality of scrapers mounted on the receptacle in positions to engage the entire surfaces of both faces of the tape and the edges thereof angularly related to said faces, said scrapers being adjustable to provide for tapes of different widths and thicknesses.
  - 55 10. A machine for folding the margin of a piece of work and applying a tape to the work having, in combination, means for feeding the work, fold-forming and fold-pressing means including a presser foot, there being a passageway in the presser foot through which the tape passes, and a roll carried by the presser foot and engaging one face of the tape.
  - 60 11. A machine for applying tape to a piece of work having, in combination, means for feeding the work and for pressing the tape against the work, a receptacle for cement, means for leading the tape through the cement, means for removing surplus cement from both faces of the tape, means for directing it upon the work in position to be engaged by the work-feeding and pressing means, and means for drawing the tape through the cement and presenting it without tension to the directing means.
  - 65 12. A machine for applying tape to a piece of work having, in combination, means for feeding the work and for pressing the tape against the work, a receptacle for cement, means for leading the tape through the cement, means for removing surplus cement from both faces and both edges of the tape, means for directing it upon the work in position to be engaged by the work-feeding and pressing means, and means for drawing the tape through the cement and presenting it without tension to the directing means.
